(57) **CLAIM**

The ornamental design for a retractable pet leash, as shown and described.

DESCRIPTION

FIG. 1 is a front perspective view of a retractable pet leash, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion encircled in FIG. 1; and,

FIG. 10 is an enlarged view of the portion encircled in FIG. 2.

The short dash-dash broken lines in the drawings illustrate the portions of the retractable pet leash, which form no part of the claimed design.

The long dash-dot-dot broken line circles representing boundaries for the enlarged views shown in FIGS. 9 and 10 form no part of the claimed design.

The trademark shown in FIGS. 1 and 3 consisting of a stylized letter G rotated 90 degrees clockwise with cat ears on top, is owned by Shenzhen Guliguli Intelligent Technology Co., Ltd.

1 Claim, 10 Drawing Sheets
